UNITED STATES PATENT OFFICE.

WILLIAM C. CROSS, OF BOSTON, MASSACHUSETTS.

PAPER-BAG MACHINE.

SPECIFICATION forming part of Letters Patent No. 239,459, dated March 29, 1881.

Application filed January 11, 1881. (No model.)

To all whom it may concern:

Be it known that I, WILLIAM C. CROSS, of Boston, Suffolk county, Massachusetts, have invented certain new and useful Improvements 5 in Machinery for Making Satchel-Bottom Paper Bags, of which the following is a specification.

My invention involves the improved method of operation—viz., the reversing of the diamond-folded bag-blank so as to bring it mouth end foremost before folding that flap of the diamond fold which overlies the body of the blank, which I have already made the subject of another application for Letters Patent. This result I have heretofore obtained in two ways—by discharging the blank upon that side of a nipper or retaining cylinder whose direction of movement is opposite to that of the blank as it passes to the cylinder, and using in conjunction with said cylinder a reversing-bar to whip the mouth end of the blank around so as to bring it to the front, as described in the application for Letters Patent above referred to, and by using in conjunction with the nipper-cylinder and the carrier which conveys the diamond-folded blank toward the same, an intermediate pocketed transferring-cylinder, which receives the blank diamond-folded end foremost and delivers it mouth end foremost to the nipper-cylinder, as described by me in still another application for Letters Patent now pending. I have devised a different arrangement of parts, which permits me to dispense with the rotary reversing-bar of the one mechanism 35 and the rotary pocketed transferring-cylinder of the other mechanism, and to discharge the blank direct upon the nipper-cylinder; and it is this last-mentioned arrangement which constitutes the improvement about to be described. 40 The said improvement can best be explained and understood by reference to the accompanying drawings, in which—

Figure 1 is a longitudinal sectional elevation of so much of a satchel-bottom paper-bag machine as needed to illustrate my invention. Fig. 2 is a like elevation of the nipper or reversing cylinder and some of its adjuncts at a different portion of its revolution from that shown in Fig. 1. Fig. 3 is an elevation of said cylinder from the discharge end of the machine. Fig. 4 is a view of a modification hereinafter referred to.

I do not show the mechanisms for making the paper tube, severing the same into bag-lengths, and making the diamond fold therein. These mechanisms may be of any suitable construction. I can use, for instance, a diamond-fold-forming mechanism such as shown and described in my Letters Patent No. 221,531, of November 11, 1879. From this mechanism the diamond-folded blank, with paste properly applied along the center line of the diamond fold by paste-wheels E' F', Fig. 1, can be delivered to the mechanism about to be described. I also remark that, in order to avoid obscurity and confusion of parts, I have omitted from the drawings the supporting-frame and gearing by which the moving parts of the machine are connected and driven. Said gearing and frame may manifestly be of any suitable construction and arrangement, as will be understood without further explanation.

The carrier by which the diamond-folded blank is conveyed to the reversing-cylinder consists of the endless power-driven tapes C and the endless power-driven apron D. Said carrier is arranged and operates substantially in the manner described in my Letters Patent No. 222,465, of December 9, 1879. In conjunction with the carrier I employ stationary inclined folding fingers or wipers E, which operate to fold the front flap of the diamond-folded blank, as described in my Letters Patent No. 232,945, of October 5, 1880. The blank, which is lettered y, is discharged from between the end rolls, d i, of the carrier diamond fold foremost, with its rear flap, or that flap, x, which overlies the body of the blank, still unfolded.

Below the discharge end of the carrier is the rotating power-driven reversing-cylinder A. This cylinder is so placed with reference to the carrier that the blank passing from the carrier will naturally fall upon that side of the rotating cylinder A whose direction of movement, as indicated by the arrow 1, Fig. 1, is in harmony with or the same as that of the blank. It is this feature that enables me to dispense with an adjunct, such as a reversing-bar or the like, which would be necessary were the blank to fall from the carrier upon that side of the cylinder marked by the arrow 2, whose direction of movement is the reverse of that which the blank has in passing from the carrier. The blank enters between the reversing-

cylinder and a pressure idle-roll, F, whose journals are hung in swinging arms *a*, mounted loosely upon a cross-rod, *b*, attached to the frame of the machine. The roll F rests by its 5 weight on the reversing-cylinder, and may, in addition, be held up against the same with yielding pressure by means of a spring or springs. In a peripheral recess, *c*, in the cylinder is an oscillating nipper, *k*, so positioned 10 that at each revolution it will come around in position just in time to take hold of the mouth end *z* of the bag-blank, as indicated in Fig. 1, where the nipper is represented in the act of descending upon the mouth end of the bag-blank. The nipper is so formed that at each 15 extreme of its movement it is entirely contained within and does not project from the periphery of the cylinder, and it bends down the mouth end of the blank into the recess *c* and binds it against the front wall of that recess, as indicated in Fig. 2, and on an enlarged scale 20 in Fig. 5, which is a side elevation of a portion of the reversing-cylinder, representing an elastic or yielding plate, *e*, in the front of the recess *c*, the same being designed to act as a 25 clamp for the mouth end of the blank in conjunction with the nipper. The nipper is operated to move forward and back at stated intervals, so as to grasp and release the blank 30 at the proper times, by means of a double arm, *f*, fixed on the projecting end of the rock-shaft *g*, upon which the nipper is mounted, and operating in conjunction with wiper-studs *h*, fixed to and projecting from the frame of the 35 machine into the path of the arm *f*, to throw the nipper forward or backward, as the case may be. A center spring may be attached to the arm *f*, so as to throw the nipper quickly over so soon as it passes the center on one side or 40 the other. The nipper, having taken hold of the mouth end of the blank, will carry the blank around the cylinder, gradually bringing the mouth end of the blank to the front, so that should the nipper make one complete revolution 45 still holding the blank it will have completely reversed the same. It is not necessary, however, that the nipper should continue its hold upon the blank for that length of time. The body of the blank naturally tends to assume 50 a vertical position, and the nipper, as it gets around to a position below the axis of the cylinder, will naturally carry the blank mouth end first into any suitable mechanism for receiving and finishing the bag. One convenient 55 form of such mechanism is shown in Fig. 1, consisting of endless tapes *G*, mounted on loose rolls or wheels *H*, which hold the tapes tightly against a portion of the periphery of the reversing-cylinder, so that the tapes shall be 60 driven by frictional contact and move in unison with the cylinder. The tapes and that portion of the cylinder against which they act constitute a carrier, which receives the blank mouth end foremost—the nipper, as soon as the 65 blank is well in the bite of the carrier, being thrown back by the lower stud, *h*, releasing the

mouth end of the blank, which mouth end rises out of the recess *c* without trouble.

A deflecting plate or table, *M*, may be used in order to support the blank and throw its 70 diamond-folded end outward as the nipper moves around with the cylinder.

The tapes *G* act to determine the line of fold, and flap *x* is folded by stationary fingers *I*, attached to the frame of the machine, and the 75 bag thus completed is discharged out from between the final rolls *H K*.

Stationary elastic or spring guard-fingers attached to the frame of the machine at *m*, with their free end extending down into small annular grooves *n* in the periphery of the reversing-cylinder, serve to direct with certainty the bag to pass out between the rolls *H K*. 80

The reversing-cylinder makes one revolution for each bag delivered to it from the carrier, 85 and its movement is so timed that the nipper is each time brought around in proper position to take the mouth end of the blank.

A modification of my improvement is shown in Fig. 4. In this modification the nipper 90 grasps the diamond-folded end of the blank instead of the mouth end, as in Fig. 1. The reversing-cylinder *A* revolves in the direction indicated by arrow 1, and the blank is delivered diamond fold foremost upon that side of 95 the reversing-cylinder whose direction of movement is the same as that which the blank has in passing to the cylinder. The nipper *k* in this modification is arranged and operated in substantially the same manner as hereinbefore described, save that it, in its forward position, lies upon the periphery of the cylinder, 100 as indicated, and not within recess *c*.

Vertically below the reversing-cylinder is a second power-driven cylinder, *L*, and tapes *G'*, 105 and folding-fingers and wipers *I'*, which, in arrangement and operation, are the same as are parts *G I*, hereinbefore described.

The blank, seized by its diamond end by the 110 nipper, is carried around in the direction indicated by the arrow until it reaches the position indicated by dotted lines in Fig. 4, at which time the bag-blank, as indicated also by dotted lines, is hanging vertically mouth end downward just over the entrance to the 115 carrier below. The nipper at this point is thrown back into the recess *c*, and releases the blank, which falls mouth end foremost into the bite of the carrier, and is there completed, and subsequently discharged from the machine. 120

Having described my invention, what I claim, and desire to secure by Letters Patent, is—

1. The combination, with the carrier, from 125 which the blank is delivered diamond-folded end foremost, and mechanism for completing the holding of the bag delivered from said carrier, of an intermediate rotating reversing-cylinder, to which the blank is delivered from 130 said carrier upon that side which moves in the same direction with the blank, and from which

said blank is delivered mouth end foremost to said completing mechanism, substantially as hereinbefore set forth.

2. The combination, substantially as hereinbefore set forth, of the carrier, the reversing nipper-cylinder, arranged so that the blank shall be delivered from the carrier diamond-folded end foremost upon that side of said cylinder which is moving in the same direction with the blank, the nipper carried by said cylinder and operated at stated times, as specified, to grasp and release the blank, and mechanism, substantially as described, for receiving and holding the blank after it has been reversed.

3. The combination of the carrier, the pressure-roll, the nipper-cylinder, and its nipper, having their movements so timed that the mouth end of the bag-blank (which passes be-

tween the said cylinder and roll diamond fold 20 foremost) shall be brought opposite to and grasped by the nipper as the latter revolves with its cylinder, substantially as and for the purpose set forth.

4. The combination, substantially as hereinbefore set forth, of the carrier, the pressure-roll, the nipper-cylinder and nipper, having their movements timed with relation to the carrier, substantially as specified, and the bag-completing mechanism, to which the blank is 30 delivered mouth end foremost from the nipper.

In testimony whereof I have hereunto set my hand this 4th day of January, 1881.

WILLIAM C. CROSS.
